UNITED STATES PATENT OFFICE.

HENRY J. GAISMAN, OF NEW YORK, AND CONRAD SCHUMACHER, OF LYNNBROOK, NEW YORK, ASSIGNORS TO AUTOSTROP PATENTS CORPORATION, OF DOVER, DELAWARE, A CORPORATION OF DELAWARE.

EDGING MACHINE.

Application filed March 23, 1923.—Serial No. 627,093.

Our invention relates to improvements in means for edging metal, such as steel, particularly for the cutting edges of instruments, and has especial reference to edging 5 of razor blades. A particular feature of our invention is to provide means to produce a fine or delicate edge upon suitable metal, either by grinding, stropping or honing it, or the same successively.

10 In carrying out our invention we provide a grinding or stropping medium, which may comprise strips of suitable abrading material or leather, mounted to be rotated or carried around bodily with respect to the 15 cutting edge of the material to be edged and also to be rotated in an axial manner with respect to said edge so as to operate upon said edge with various kinds of contact to produce a desired finish on the cutting edge 20 of the material, which may be used for razor blades or other instruments.

Our invention also comprises novel details of improvement that will be more fully set forth hereinafter and then pointed out 25 in the claims.

Reference is to be had to the accompanying drawings forming a part hereof, wherein—

30 Fig. 1 is a cross-sectional view on line 1, 1, of Fig. 2, of a machine embodying our invention, illustrating the relation of parts more or less diagrammatically;

Fig. 2 is a partly sectional side elevation 35 of the machine;

Fig. 3 is a plan view partly in section on line 3, 3, in Fig. 2;

Fig. 4 is a detail end view partly in section on line 4, 4, in Fig. 2;

Fig. 5 is a partly sectional side elevation 40 of Fig. 4;

Fig. 6 is an end view illustrating driving means for axially rotating the grinding or stropping media;

Fig. 7 is a side view illustrating the driving means of Fig. 6;

Fig. 8 is a detail of guiding means for the material to be stropped;

Figs. 9 and 10 are sectional details respectively on lines 9, 9 and 10, 10 of Fig. 8; and

50 Fig. 10^a is a cross-section of strip A.

Similar numerals of reference indicate corresponding parts in the several views.

Upon a suitable support 1 is secured a base or frame 2 provided with spaced standards 3. A shaft 4 is journaled in suitable 55 bearings on said base and is shown provided with fast and loose pulleys 5 and 6 for rotating said shaft. Shaft 4 is shown provided with a gear 7 in mesh with a gear 8 secured on a shaft 9, the gear 7 also being 60 in mesh with an idle gear 10 on a shaft 11 spaced from shaft 4, the gear 10 being in mesh with gear 12 secured upon the shaft 13. The shaft 9 is journaled in bearings in a bracket or arm 14 that is movably supported on or concentric with shaft 4 as a center and extends upwardly therefrom, and shaft 13 is journaled in bearings upon a bracket or arm 15 journaled upon or concentric with shaft 11 and extending upwardly 70 therefrom. The brackets or arms 14, 15 are shown located on opposite sides of uprights 3 and are adjustably connected with said uprights, as to a tie bar 3^a secured thereto, for which purpose we have shown bar 75 3^a provided with a projection 3^b receiving a pivot pin 16 that passes through the adjacent ends or eyes of screws 17, 18, the outer ends of which screws pass through openings 80 in projections 14^a, 15^a of arms 14, 15 respectively, said screws being secured in set position by means of nuts 19 adapted to be adjusted against the projection 14^a, 15^a, (Fig. 3). The arms 14, 15 may be adjusted toward and from each other with respect to 85 the opposite sides of uprights 3. The shafts 9 and 13 respectively carry pairs of spaced heads or spiders 20, between which are journaled shafts 21, there being six such shafts shown supported by each pair of heads or spiders 20, although any suitable number of such shafts may be provided for each pair of heads. The shafts 21 carry stropping or 90 grinding media, which may be of leather or other suitable material, adapted to engage the cutting edge *a* of an article to be stropped, such as a strip of steel A, which may be utilized for safety razor blades. We have shown each of the shafts 21 equi-distantly disposed respecting the axes of the 95 corresponding shafts 9 and 13, the shafts 21 being provided with rolls 22, secured to said shafts by pins 23 or in any other desired manner. Said rolls are shown provided 100

with spirally disposed peripheral grooves 24 in which are located the media before referred to, such as strips of leather or other suitable material 25, (Fig. 2), whereby said strips are helically disposed around the rolls 22 and have their outer surfaces exposed to engage the cutting edge *a* of the strip A. The strips 25 may be secured in the peripheral recesses 24 of rolls 22 by any suitable means, such as by an adhesive. The strips 25 may be of suitable material adapted to grind or reduce the edge *a* by contact therewith, or have a grinding substance applied thereto such as ground emery, in any suitable way, or said strips may be of leather, canvas or the like, relatively smooth on the working surface, to serve for stropping or honing edge *a* of strip A. During the rotation of shafts 9 and 13, by means of the gearing before described, the rolls 22 are rotated bodily around the axes of their shafts 9, 13, with respect to the strip *a* passing between them, so that the outer surfaces of the media or strips 25 may engage the sides of strip A or its edges *a*. It will be observed from the drawings that the respective sets of stropping rolls are located on opposite sides of the strip A, which is guided to travel longitudinally through a guide 26 which may be supported in vertical slots 3' of the standards 3, screws 27 carried by said standards serving to adjust the guide 26 in an upward direction and retain the guide in set position, (Figs. 4 and 5). The guide 26 may be of any suitable construction having an upper interior space 26^a to receive strip A, (Fig. 9). The guide 26 is shown formed in two pieces of metal secured together by screws 29 and provided with longitudinally disposed offset portions 26^b which oppose and provide the guiding recess 26^a, (see Figs. 8, 9 and 10). Central guiding members 26^c are set relatively close together to receive strip A between them at the portion where the grinding or stropping is performed, and secured to guide 26, (Figs. 8 and 10).

In the example illustrated in Fig. 1 the rolls 22 at the right hand side are adapted to be rotated bodily clockwise, in the direction of the arrow *b*, and the rolls 22 at the left in said figure are adapted to be rotated bodily anti-clockwise, in direction of the arrow *c*, and said rolls on opposite sides of the machine are shown so disposed as to alternately engage the edge *a* of strip A as said rolls rotate bodily. Means are also provided to rotate the rolls axially while they are being bodily rotated around the axes of their respective supporting shafts 9 and 13, so that the stropping media or strips 25 will not only engage the strip A by reason of their bodily rotation, but also by reason of their axial rotation, as in a planetary manner. For producing the axial rotation of rolls 22 we pro-

vide said rolls with pulleys 30, which may be secured to the respective shafts 21, which pulleys are adapted to engage an endless belt 31 during bodily rotation of said pulleys with their respective rolls, (Figs. 6 and 7). The endless belt 31 passes from a drive pulley 32 over guiding pulleys 33 on opposite sides of the machine, and has bights or loops 31^a, 31^b above said pulleys which respectively enclose some of the pulleys 30 on opposite sides of the machine, said belt at its portion below said bights or loops also passing over guide pulleys 34 on opposite sides of the machine (Figs. 3 and 7). The pulleys 33, 34 are arranged in pairs and are carried upon shafts or pivots 35 supported by arms 36 projecting outwardly from the frame 2. The belt 31 is driven in the direction of the arrows in Fig. 6 by means of pulley 32, and as the pulleys 30 are rotated bodily around the axes of their shafts 9 and 13 and make contact with the respective bights of the belt 31 said pulleys are rotated axially respectively in the direction of the arrows *d* and *e* in Fig. 6, that is to say the pulleys and their rolls 22 are rotated axially clockwise on one side of the machine, as on the right hand side of Fig. 6, and axially anti-clockwise at the left hand side of Fig. 6, whereby the stropping media or strips 25 will be rotated correspondingly in contact with the opposite sides of strip A, in a direction toward the cutting edge of the strip. By adjusting the arms 14, 15 toward the cutting edge *a* of strip A the stropping or grinding media or strips 25 not only engage said edge of strip A with a so-called wiping stroke by reason of their bodily rotation, but also with a relatively sliding action against such edge by reason of their axial rotation and their helical or spiral action against said edge.

The pulley 32 may be driven in any suitable way, being illustrated mounted upon a shaft 37 journaled in suitable bearings on the main frame to be driven in any suitable manner. The belt 5^a, for the drive pulleys 5 and 6, is adapted to operate on fast and loose pulleys 38, 39 on shaft 37, whereby shafts 4 and 37 are rotated together.

The strip A may be fed between the respective sets of rolls 22 in any suitable manner, such as from a reel B on one side of the machine to be pulled by drawing rolls C on the other side of the machine. Our improvements may be incorporated in any desired or well known machine adapted to first grind the edge *a* of strip A to reduce the cutting edge *a* to any desired condition before being operated upon by the described stropping or honing devices, or the grinding may be performed in one machine and the stropping or finishing in a separate machine.

While we have illustrated sets of rolls 22 on opposite sides of the machine, adapted to

successively or alternately operate on opposite sides of the edge of strip A, it will be understood that where the cutting edge of a strip is to be ground or stropped only on one side thereof, only one set of the rolls 22 need be used to operate on the corresponding side of the strip.

From the foregoing description it will be understood that as the strip A advances adjacent to the rolls 22 the latter will be rotated bodily as well as axially in contact with the edge portion of the strip, and that the grinding or stropping media 25 will continue to engage the cutting strip with alternating successive touches from the corresponding series of rolls 22, so that as the strip advances along said rolls the same part of the strip will be successively engaged by succeeding media 25, whereby a very fine and delicate edge may be produced upon the strip in an accurate and expeditious manner. The rolls 22 may be used in our machine to first grind the strip A for an edge and then strop it, spaced sets of rolls being provided for such purpose, or the rolls may be arranged to grind or to strop only as may be desired.

The finished strip may be divided into shorter lengths for any desired purposes, such as for razor blades. Instead of passing a strop through the machine for grinding, stropping or honing its cutting edge a strip of suitable length may be placed in the guide or holder 26 to be ground or stropped while held stationary, to be removed and replaced when finished, and so on successively.

We term the strip or strips 25 a rubbing medium or media whether adapted for grinding or stropping the material or strip A since, as such medium passes said material or strip it will engage the same with a rubbing action. Although we have shown the medium 25 in the form of a strip spirally disposed on its roll 22 it will be understood that said medium may be in any other desired form adapted to engage material A when passing the same.

Having now described our invention, what we claim is:

1. An edging machine comprising a rubbing medium, means to rotate said medium bodily at one side of an article to be edged into and out of contact therewith, and means to rotate said medium axially in contact with the article during bodily rotation of the medium, the said bodily and axial rotations of said rubbing member being continuous before, during and after contact with the article.

2. An edging machine comprising a plurality of spaced rubbing media, means to rotate said media bodily in the same direction at one side of an article to be edged into and out of contact therewith, and means to ro-

tate each of said media axially in contact with the article during their bodily rotation, the said bodily and axial rotations of said rubbing media being continuous before, during and after contact with the articles.

3. An edging machine comprising a plurality of spaced rolls provided with peripheral rubbing media, means to support said rolls at one side of an article to be edged for rotation on their axes and for bodily rotation, means to rotate said rolls bodily into and out of contact with said article, and means to rotate said rolls axially in contact with the article during their bodily rotation, the said bodily and axial rotations of said rubbing media being continuous before, during and after contact with the articles.

4. An edging machine comprising a shaft, a plurality of edging rolls carried by said shaft and spaced therefrom, means to rotate said shaft to rotate said rolls bodily there-around, means to rotate said rolls axially in contact with the article during their bodily rotation around the axis of the shaft, and means to guide an article at one side of the path described by the outer surfaces of said rolls during their bodily rotation, the said bodily and axial rotations of said edging rolls being continuous before, during and after contact with the article.

5. An edging machine comprising a plurality of spaced edging rolls disposed substantially concentrically around a common axis, means to rotate said rolls bodily around said axis continuously and successively into and out of contact with an article to be edged, means to rotate said rolls axially in directions corresponding to the direction of their bodily rotation, and means to guide an article at one side of the path described by the outer surfaces of said rolls during their bodily rotation.

6. An edging machine comprising means to guide and feed a strip to be edged, a plurality of spaced edging rolls pivotally supported on a common axis on one side of said strip, means to rotate said rolls bodily on said side of said strip continuously and successively into and out of contact therewith, and means to rotate said rolls axially respecting said strip.

7. An edging machine comprising means to guide a strip to be edged, an arm movably supported adjacent to said guiding means, means to adjustably retain said arm with relation to said guiding means, edging rolls, means to support said rolls for bodily rotation with respect to said guiding means, and means to bodily rotate said rolls.

8. An edging machine comprising means to guide a strip to be edged, an arm movably supported adjacent to said guiding means, means to adjustably retain said arm with relation to said guiding means, edging rolls, means to support said rolls for bodily rota-

tion with respect to said guiding means, means to bodily rotate said rolls, and means to rotate said rolls axially.

9. An edging machine comprising means to guide a strip, arms movably supported on opposite sides of said guiding means, means to adjustably retain said arms respecting said guiding means, edging rolls, means supporting the edging rolls upon each of the 10 arms in spaced relation to one another, and means to bodily rotate said rolls.

10. An edging machine comprising means to guide a strip, arms movably supported on

opposite sides of said guiding means, means to adjustably retain said arms respecting 15 said guiding means, edging rolls, means supporting the edging rolls upon each of the arms in spaced relation to one another, means to bodily rotate said rolls, and means to axially rotate said rolls. 20

Signed at New York city, county and State of New York, this 21st day of March, 1923.

HENRY J. GAISMAN.
CONRAD SCHUMACHER.
